Attorneys

UNITED STATES PATENT OFFICE.

RALPH RAYMOND REED, OF OAKLAND, CALIFORNIA.

DETACHABLE TOOTH FOR HANDSAWS.

Application filed June 27, 1921. Serial No. 480,696.

To all whom it may concern:

Be it known that I, RALPH R. REED, a citizen of the United States, residing at Oakland, in the county of Alameda, and 5 State of California, have invented certain new and useful Improvements in Detachable Teeth for Handsaws; and I do declare the following to be a full, clear, and exact description of the invention, such as will enable others skilled in the art to which it 10 pertains to make and use the same.

This invention relates to detachable teeth for hand-saws such as are used by carpenters and the like, and it has for its principal 15 object to provide a toothed strip for connection to the lower edge of a flexible blade simulating that found on hand-saws at this time.

The principal feature of the invention is 20 that the manner in which the toothed member is connected with the blade does not limit or interfere with the depth of the cut as do other saws embodying removable teeth.

A further aim of the invention is to provide a hand-saw of this class which embodies all of the advantages of the ordinary hand-saw such as used by a carpenter and has the additional advantages of enabling the teeth when worn and displaced, to be removed and a new set of teeth substituted 30 therefor.

A still further aim of the invention is to provide a saw having removable teeth which are connected with the blade by means of 35 self-gripping resilient jaws. Hence, the employment of special clamping devices for holding the teeth in place is entirely overcome and the tooth-strip can be easily and readily removed from the blade by hand.

40 Other features and advantages of the invention will become apparent during the course of the following description.

In the accompanying drawings forming a part of this specification and in which like 45 numerals are employed to designate like parts throughout the same:

Figure 1 is a side elevational view of a saw constructed in accordance with this invention.

50 Figure 2 is an enlarged detail section taken substantially on the plane of the line 2—2 of Fig. 1.

Figure 3 is an elevational view with parts 55 moved.

Figure 4 is an elevational view of one end of the removable toothed strip.

Figure 5 is an elevational view of a slightly modified form of the invention.

Figure 6 is an enlarged detail section 60 taken substantially on the plane of the line 6—6 of Fig. 1.

Figure 7 is an elevational view with parts in section of the blade and toothed strip of this form of the invention disconnected from 65 one another.

Figure 8 is a top edge view of the toothed strip.

Referring to the drawings by numerals, 1 designates a flexible blade of the same shape 70 as blades now found on carpenters' handsaws. This blade is provided on its lower edge with integral resilient jaws 2 which provide between themselves a channel in which the upper edge of a flexible strip 3 is 75 received. It is to be pointed out here that the jaws 2 are sufficiently resilient to render themselves self-gripping so that after the strip 3 is inserted between them, they will automatically frictionally grip it and hold it 80 in place. The strip 3 referred to is provided on its lower edge with alternately bent teeth 4 which are properly set previous to the attachment of the strip 3 to the afore- 85 said blade. In order to prevent longitudinal shifting of the strip 3, the blade is equipped at its opposite ends with stops 5, which may be integral therewith or otherwise rigidly secured thereto, these being ranged at the opposite ends of the channel 90 and the adjacent ends of the strip 3 being engaged therewith. The manner described of detachably connecting the toothed strip with the blade is not altogether essential and I do not wish to be limited to this specific 95 arrangement. In fact, I have shown another way in which the invention can be carried out. I therefore direct attention to Figs. 5 to 8 inclusive.

Referring to the figures above mentioned, 100 it will be seen that the toothed strip 3^a is provided in its upper edge with a channel 4^a the side walls of which constitute resilient jaws 5^a. The blade 1^a has its lower edge thinned as indicated at 6 and this portion of the blade is received between the jaws 5^a and frictionally held. The ends of the channel 105 4^a are, like the channel in the lower edge of the blade described in Figures 1 to 3, closed by blocks constituting stops 7 against which 110

the ends of the reduced portion 6 of the blade abuts. Here, I wish to state that in both forms of the invention, the teeth of the saw are properly set to form a kerf of 5 a width sufficiently large to permit passage of the blade through this kerf without any interference. I may state that in many forms of saws with which I am familiar, the constructions are such that the detachable 10 teeth are not directly connected to a flexible blade but some sort of a holder is provided and this holder limits the depth of the cut. However, this is not the case with the construction and arrangement that I employ.

15 The manner of attaching and detaching the strip which carries the teeth is obvious from the drawings and it is therefore thought unnecessary to go into more detail.

Since probably the best results may be obtained with the construction and arrangement herein shown and described, this is

taken as a preferred embodiment of the invention. However, I wish it to be understood that minor changes coming within the scope of the subjoined claim may be resort- 25 ed to if desired.

I claim:

A hand-saw comprising a flexible blade and a flexible toothed strip, one of which is formed along one edge with a groove terminating short of the ends of this part to provide shoulders, the side portions of said groove being resilient to provide jaws, the other part being received in said groove and gripped tightly and held in operative place 30 35 by said jaws, said last named part abutting the aforesaid shoulders to prevent relative sliding movement of said parts.

In testimony whereof I have hereunto set my hand.

RALPH RAYMOND REED.
